CLAIM

The ornamental design for smoker's article, as shown and described.

DESCRIPTION

FIG. 1 is a perspective view of smoker's article showing the front, top, and left side of our new design as viewed from the right side of the page;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top elevational view thereof;
FIG. 7 is a bottom elevational view thereof;
FIG. 8 is a perspective view of another embodiment of a smoker's article showing the front, top, and left side of our new design as viewed from the right side of the page;
FIG. 9 is a front elevational view thereof;
FIG. 10 is a rear elevational view thereof;
FIG. 11 is a left side elevational view thereof;
FIG. 12 is a right side elevational view thereof;
FIG. 13 is a top elevational view thereof;
FIG. 14 is a bottom elevational view thereof;
FIG. 15 is a perspective view of another embodiment of smoker's article showing the front, top, and left side of our new design as viewed from the right side of the page;
FIG. 16 is a front elevational view thereof;
FIG. 17 is a rear elevational view thereof;

FIG. 18 is a left side elevational view thereof;
FIG. 19 is a right side elevational view thereof;
FIG. 20 is a top elevational view thereof;
FIG. 21 is a bottom elevational view thereof;
FIG. 22 is a perspective view of another embodiment of a smoker's article showing the front, top, and left side of our new design as viewed from the right side of the page;
FIG. 23 is a front elevational view thereof;
FIG. 24 is a rear elevational view thereof;
FIG. 25 is a left side elevational view thereof;
FIG. 26 is a right side elevational view thereof;
FIG. 27 is a top elevational view thereof;
FIG. 28 is a bottom elevational view thereof;
FIG. 29 is a perspective view of another embodiment of smoker's article showing the front, top, and left side of our new design as viewed from the right side of the page;
FIG. 30 is a front elevational view thereof;
FIG. 31 is a rear elevational view thereof;
FIG. 32 is a left side elevational view thereof;
FIG. 33 is a right side elevational view thereof;
FIG. 34 is a top elevational view thereof;
FIG. 35 is a bottom elevational view thereof;
FIG. 36 is a perspective view of another embodiment of smoker's article showing the front, top, and left side of our new design as viewed from the right side of the page;
FIG. 37 is a front elevational view thereof;
FIG. 38 is a rear elevational view thereof;
FIG. 39 is a left side elevational view thereof;
FIG. 40 is a right side elevational view thereof;
FIG. 41 is a top elevational view thereof;
FIG. 42 is a bottom elevational view thereof;
FIG. 43 is a perspective view of another embodiment of smoker's article showing the front, top, and left side of our new design as viewed from the right side of the page;
FIG. 44 is a front elevational view thereof;
FIG. 45 is a rear elevational view thereof;
FIG. 46 is a left side elevational view thereof;
FIG. 47 is a right side elevational view thereof;
